UNITED STATES PATENT OFFICE.

HAROLD G. WARR, OF PARK RIDGE, ILLINOIS, ASSIGNOR TO THE P & M COMPANY, OF CHICAGO, ILLINOIS, A CORPORATION OF ILLINOIS.

RAIL ANCHOR.

Application filed July 20, 1927. Serial No. 207,195.

My invention relates to rail anchors and more particularly to one piece anchor devices adapted to be driven into spring gripping engagement with the top and bottom surfaces of one flange of a rail base.

The principal object of the invention is to provide means whereby an anchor device of the above character made to fit a rail base of one size may be applied to a rail having a base flange of a different size or contour. In this connection, I contemplate as a more specific object, the provision of means which will serve as a stop to limit the applying movement of the anchor device and thereby avoid excessive spreading of the rail gripping portions of the anchor; which means cannot be removed during the application of the anchor or after it has been driven to its applied position on a rail; and which, when the device is applied to a relatively narrow base flange, will prevent the anchor from skewing about a vertical axis to an objectionable angle, but which will serve to increase the grip of the device on the rail when the anchor is subjected to a moderate skewing action.

The invention has for further objects the new and improved construction, arrangements, and combinations of parts hereinafter described and claimed for carrying out the above stated objects and such other objects as will appear from the following description of the two specific embodiments shown in the accompanying drawing.

In the drawing:

Fig. 1 shows a one-piece anchor device, of a type now in general use, made of such dimensions as to fit a rail base of a predetermined width and thickness.

Fig. 2 shows the same anchor device in connection with one embodiment of my improved stop member applied to a rail base which is relatively narrow and thick with respect to the rail base shown in Fig. 1.

Fig. 3 is a view similar to Fig. 2 showing the same anchor device and a modified form of stop member applied to a rail base which is both narrower and thinner than the rail base shown in Fig. 1.

Fig. 4 is a sectional view taken on line 4-4 of Fig. 2, and

Fig. 5 is a view in perspective of the stop member shown in Fig. 3.

In order to illustrate the principles embodying my invention and the advantages to

be obtained by its use, I have illustrated herein a one-piece rail embracing member applied to rail bases of three different sizes. It should be understood, however, that the form of anchor device 10, herein shown, is employed merely for the purpose of illustration and that various other forms of rail embracing members may be used instead of the form herein shown.

The rail embracing member 10 consists of a bar formed at one end with a hooked jaw portion 11 adapted to be driven into gripping engagement with the top and bottom surfaces of the rail base and is formed at the other end with a shoulder 12 which snaps over the opposite edge of the rail base when the jaw end 11 has been driven to its normal gripping position on the rail base. In the particular form of rail embracing member herein shown, the gripping surfaces 13 and 13^a of the jaw end of the member 10 are spread apart slightly by the movement of the member 10 to its rail-gripping position so as to exert spring pressure on the top and bottom surfaces of the rail base. This spring action of the jaw end 11 serves also to hold the shoulder 12 in its normal position so as to lock the embracing member in its normal operative position on the rail base.

It is important, in applying anchors which rely for their grip upon distortion of their jaw ends or other portions of the rail-embracing member, to limit the applying movement of the member so as to not subject the member to excessive distortion. The excessive distortion tends to make a permanent set in the distorted portion, and thereby makes the anchor unsuitable for re-application to other rails. In order to avoid these conditions the one-piece type of anchor is ordinarily made to fit a rail base of predetermined size and cross-sectional contour. Rails of different standard contours, but of the same weight per linear yard, may differ in the widths and thicknesses of their base flanges, but there is one point on each flange that will correspond in thickness to some other point on the other rail bases. In many cases, the point of uniform thickness will appear at substantially the same distance from the opposite side of the rail base.

My present invention aims to take advantage of the above conditions by providing a separately formed member 14 adapted to be positioned in the jaw portion 11 of

the rail embracing member so as to prevent the rail embracing member from being driven beyond its intended gripping position when it is applied to a rail base somewhat narrower than the rail base shown in Fig. 1. In Figs. 2 and 4, the member 14 is illustrated as consisting of a metal strip formed with downturned ends 15 and 16 which embrace opposite side faces of the jaw portion 10 of the member 10. The member 14 preferably fits loosely in the space underlying the jaw 11^a, but the down-turned ends 15 and 16 are of sufficient length to prevent removal of the member 14 when the jaw 11^a is hooked over the edge of the rail base. The width of the member 14 is such that it comes into contact with the edge 17 of the rail base 18 and prevents any substantial further movement of the member 10 as soon as the shoulder 12 snaps over the opposite edge of the rail base.

The rail embracing member herein shown is made to fit the rail base 19, shown in Fig. 1, and is applied by hooking the jaw 11^a over the base flange at one side of the rail and then driving the member 10 transversely of the rail by striking the jaw end 11 with a sledge or suitable applying implement until the shoulder 12 snaps over the opposite edge 30 of the rail base. In this connection, it will be noted that both of the rail bases shown in Figs. 1 and 2, are of substantially the same thickness "x" at substantially the same distance Y from the opposite edge of the base. It will therefore be seen from an inspection of Figs. 1 and 2 of the drawing, that by inserting the member 14 in the jaw end 11 of the embracing member 10, driving the jaw portion onto the narrower base 18, 40 the member 14 will serve to limit the applying movement of the member 10 so that the shoulder 12 will snap over the edge 20 of the base 18 when the gripping surfaces 13 and 13^a reach their intended gripping position. It will also be noted that the said gripping surfaces will grip the base flanges 18 and 19 at points of substantially equal thickness. The stop member 14 bearing against the vertical surface 17 of the base 50 18 will prevent any substantial skewing of the anchor about a vertical axis. The clearance 21 in Fig. 1 and the clearance 22 between the stop member 14 and the root of the jaw portion 11 in Fig. 2, permit the anchor to be applied to slightly oversized rails, such, for example, as may result from the wearing of or the adjustment of the rolls with which the rails are formed.

In Fig. 5, I have shown a modified embodiment in which the stop member 14^a in addition to having flanges 15^a, 16^a, which fit over the side faces of the rail embracing member, is formed also with an extension 23, intended to fit between the bearing surface 13 of jaw 11^a and the top inclined sur-

face of a relatively narrow and somewhat thinner base flange than that for which the member 10 was made. With this form of clip member, the embracing member 10 may be applied to rails having base flanges of less thickness than either of the rails 18 and 19, shown in Figs. 1 and 2.

I claim:

1. A rail anchor comprising a rail embracing member formed with a jaw portion 75 adapted to be driven into gripping engagement with the top and bottom surfaces of the base portion of a rail, and means carried in the space below the jaw of said member to limit the applying movement thereof, whereby said embracing member may be applied to rails having base flanges of different widths.

2. A rail anchor comprising a rail base embracing member adapted to be driven into gripping engagement with the top and bottom surfaces of the rail base, and a stop member embracing a portion of said rail gripping member and adapted to engage the vertical edge of the rail base when said gripping member is driven to its applied position.

3. A rail anchor comprising a rail base embracing member formed with a hook shaped jaw portion adapted to be driven into gripping engagement with the top and bottom surfaces of a rail base, and a separately formed stop member embracing a portion of the jaw end of the first mentioned member and adapted to engage the vertical edge of 105 the rail base to limit the applying movement of said first mentioned member, whereby said first mentioned member may be applied to rails of less width than for which said first mentioned member is made.

4. A rail anchor comprising a rail base embracing member formed with means adapted to be driven into spring gripping engagement with the top and bottom surfaces of a rail base of predetermined size, 110 and a separately formed member carried by the said embracing member to accommodate the embracing member to a rail base of smaller size.

5. A rail anchor comprising a rail base embracing member formed at one end with a jaw portion adapted to be driven into spring gripping engagement with the top and bottom surfaces of a rail base of predetermined size, and a separately formed stop member comprising a metal strip provided with down-turned ends adapted to fit over a portion of the jaw end of the embracing member and adapted to engage the longitudinal edge of the rail base when the embracing member is applied to rail bases of less width than for which it was made.

6. A rail anchor comprising a rail base embracing member formed at one end with a jaw portion adapted to be driven into 130

- gripping engagement with the base portion of a rail of predetermined size, and a separately formed stop member comprising a metal strip provided with downturned ends 5 adapted to fit over the body portion of the embracing member in a position below the jaw of said member and adapted to be engaged with the longitudinal edge of the rail base when the embracing member is driven 10 to its applied position; the down-turned ends of said stop member being of sufficient length to prevent removal of the stop member when the embracing member is in its applied position.
- 15 7. A rail anchor comprising a rail base embracing member formed with a jaw portion adapted to be driven into spring gripping engagement with the top and bottom surfaces of a rail base of predetermined 20 size, and a separately formed stop member comprising a metal strip provided with down-turned ends adapted to fit over a portion of the jaw end of the embracing member and to engage the edge of the rail base 25 when the embracing member is applied to rail bases of less width than for which it was made and formed with a portion adapted to lie between a surface of the rail base and a gripping surface of said embracing 30 member.
8. A rail anchor comprising a rail base embracing member adapted to be driven into spring gripping engagement with the top and bottom surfaces of a rail base of predetermined 35 size, and a separately formed member for accommodating the embracing member to rail bases of smaller size, comprising

a metal strip formed with a portion adapted to fit between the inclined top surface of the rail base and a gripping surface of said embracing member and provided with downturned end portions adapted to engage the longitudinal edge of the rail base to limit the applying movement of said embracing member.

40 9. A rail anchor comprising a rail base embracing member formed with a jaw portion adapted to be driven into gripping engagement with the top and bottom surfaces of the base portion of a rail, and separately 45 formed means interposed between the rail and said embracing member for limiting the applying movement of the said embracing member.

10. A rail anchor comprising a rail base 50 embracing member adapted to be driven into gripping engagement with the top and bottom surfaces of the rail base and a stop member interposed between the rail base and a portion of said embracing member to 55 maintain the embracing member in its operative position on a rail.

11. A rail anchor comprising a rail base 60 embracing member formed with means adapted to be driven into spring gripping engagement with the top and bottom surfaces of a rail base of predetermined size, and a separately formed member interposed between the rail and a portion of said embracing member to accommodate the embracing member to a rail base of smaller 65 size.
